UNITED STATES PATENT OFFICE

2,160,998

PLANT PACKAGE

Clarence E. Wilson, Manchester, Conn.

Application May 21, 1936, Serial No. 81,074

1 Claim. (Cl. 47—37)

This invention relates to improvements in plant packages for storing and shipping plants, and its objects are as follows:

First, to provide a plant package which is especially made with a view to the utmost in simplicity, so that it can be used in large quantities for packing, sustaining and shipping growing plants without adding to the current cost thereof.

Second, to assemble the earth plug together with its bottom and top in cartridge form, and to load the shell with the cartridge by pushing it into one end of the shell as a unit and thereupon holding it in place by inserting a follower ring.

Third, to use a straight-sided shell composed of disintegrable material, which is braced at its ends by rings which are inserted on the inside so as to avoid any obstruction on the outside, one of said rings (the top one) being used as a means for stretching and clamping a piece of otherwise limp, transparent, gas-proof material in place across the shell to provide a window.

Fourth, to provide the package with a liner which is impregnated with a fertilizing chemical that will be given off and absorbed by the plant.

Fifth, to make said liner of soluble material so that it will eventually disintegrate with the shell in the soil when the package is planted as herein contemplated.

Sixth, to slit or otherwise puncture the package so that moisture can get out or in after planting, use being made of a tool which is especially adapted to do the slitting.

Other objects and advantages will appear in the following specification, reference being had to the accompanying drawing in which:

Figure 1 is a perspective view of the improved plant package, looking down into the inside through the top window.

Figure 2 is a detail perspective view illustrating the unit formation of the earth plug and the end covers, also showing how the unit is pushed into the shell.

Figure 3 is a longitudinal section of the plant package.

Figure 4 is a detail sectional view of a modification in the form of the top window.

Figure 5 is a detail perspective view of a portion of the inner fertilizing liner.

Figure 6 is a detail perspective view of the package showing how it is slit before planting.

Figure 7 is a perspective view of the slitting tool.

Figure 8 is a detail section of a modified bottom.

In carrying out the invention provision is made of a shell 1, made in straight-sided form whether

cylindrical or angular in cross section. It is composed of disintegrable material so that when a portion of the package is buried in the ground when setting the plant, said portion will gradually disintegrate.

An important feature of the invention is to provide an insertable unit consisting of the earth plug 2, bottom 3, top 4 and surrounding liner 2a. In actual practice this unit is ejected in cartridge form from the machine which produces such units at a rapid rate, the end covers being emplaced below and above the earth plug so that the unit is ready to be inserted into one end of the shell as indicated by the arrow a (Fig. 2).

The advantage of having the unit as one of the elements of the plant package is the clean manner and facility with which it can be handled. A substantially uniform amount of earth is contained by every plug 2, and inasmuch as the plug compactly contains the roots 5 of the plant 6 the unit is capable of being pushed directly home until a stop ring 6a is engaged by the top 4, with little or no loss of earth. The ring 6a holds the top 4 in place and prevents the plant cartridge from moving out of place toward the window in the top of the package. The unit is of the exact form of the inside of the shell.

An opening 7 in the top 4 contains the crown 7a of the plant. The space 8 between the cover 4 and the transparent window 9 is a greenhouse, in a sense, providing room for a limited development of the plant. The ability of the purchaser to see through the window is a sales promoter. The window lets light through and this aids the growth of the plant.

After pushing the unit into the shell 1 a follower ring 10 is inserted in the bottom end of the shell to hold the unit in place. This ring serves as one of two braces for the ends of the shell. The other ring 11 at the top of the shell both stretches the material of the window 9 and clamps its margin 12 in place across the shell.

Usually the window 9 is composed of a piece of Cellophane. This is limp and easily handled. Further, it provides a gas-proof closure. The piece is cut oversize in circular form and laid on the end of the shell. The ring 11 is then centered on the piece, and as the ring is pushed in it folds the margin 12 of the window between the shell and ring. The ring is a close fit to begin with, and since it must accommodate the margin 12, it follows that the ring will be wedged in position, in addition to the ring stretching and clamping said piece.

Thus it is clear that the straight-sided shell 1

is braced at its ends by the rings 10, 11 and since these are inserted on the inside it follows that all outside obstructions are avoided. It is a particular purpose to make the package as simple as possible. Generally its parts are made of treated cardboard, excepting the window 8, and this sustains the plant by conserving the moisture. The package is air-tight, or as nearly so as it is possible to make it.

10 As to the treated cardboard, reference is made to the liner 2a. This is preferably corrugated as at 15 (Fig. 5), but not necessarily so. It is impregnated with a chemical fertilizer 16, which, as already pointed out, will be given off and absorbed by the plant. This is a benefit to the plant not only while dormant in the package, but also when the planting is done.

15

Figure 4 illustrates a modification whereby the window is brought flush, or substantially so, 20 with the adjacent end of the shell, instead of being depressed below the end as in Fig. 3. The window-piece 8a is marginally clamped at 12a between a pair of rings 13, 14. The pair is then inserted in the end of the shell 1a, all other 25 parts of the package (not shown) being precisely as already described.

Fig. 6 shows how the package is slit at 17, or punctured in some other way, to provide 30 openings 18 for the passage of moisture when planted. Preparatory to the latter step the top of the package is removed above the line 19, exposing the plant from the crown 7a up. The 35 entire remainder is then planted, the paper substance disintegrating in time, and the fertilizing chemicals of the liner 2a being absorbed by the plant.

Fig. 7 illustrates a convenient tool for doing the foregoing slitting. This tool can be made in a variety of ways, but one way is to fasten two 40 razors or other blades 20 as at 21 between the opposite sides of a spacer 22 and the inner sides of the sheath end 23 of the handle 24. The blades are thus held in parallelism, and since

only matching corners are exposed it is easy to penetrate the cardboard shell and then make the slits by drawing the tool along as far as desired. The beveled end 25 of the spacer limits the penetration, consequently the depth of the 5 cut so that the plant roots are not injured.

The planting procedure is briefly summarized: The shell 1 is cut around approximately on a level with the crown 7a of the plant, or a little above the line 19 (Fig. 6). The upper part is 10 removed, but the lower part is punctured so as to provide openings through which moisture, also the roots can pass. After immersing the package in water for a few minutes the bottom and top covers 3 and 4 are removed from the 15 plug 2 and the remainder is planted. At this stage the plant is so pliable and small from the crown up that the cover 4 is readily slipped up and off, the hole 7 being quite large enough. In the event it is not desired to plant the shell with 20 the earth plug, the latter is simply removed and set in the ground in the ordinary way.

In conclusion, reference is made to Fig. 8 which illustrates a modified construction in the bottom formation. The follower ring 10b clamps the 25 margin 12b of a circular sheet of tough paper 3b or other pliable material in place on the shell 1b either in the exact position shown, or in an inverted position so that the bottom comes flush with the lower edge of the shell, or the bottom 30 may be clamped onto the outside of the shell.

I claim:

A plant package comprising a shell, a bottom fixed in one end of the shell, a top inserted in the shell and having an opening, a liner interposed between the bottom and top, said liner being corrugated so that the flutes provide an ample rest for the top, and a stop ring inserted in the shell, pressing on the margin of the top and being situated within the confines of the 40 liner-flutes.

CLARENCE E. WILSON.
